MOTION PICTURE FILM REEL

Richard S. Hirschland, Closter, and Adrian A. Cohen and
Stanley R. Cohen, New Milford, N.J., assignors to
George V. Clark Co., Inc., a corporation of New York
Filed May 19, 1960, Ser. No. 30,349

1 Claim. (Cl. 242—71.8)

The present invention relates to motion picture film reels, more particularly of the type characterized by a pair of flanges having a hub between them, each flange including an outer peripheral rim interconnected with a base portion by a plurality of spokes.

It is an object of the present invention to provide motion picture film reels of this type, in which improved flexibility is imparted to the flanges without permanent deformation.

Another object of the present invention is the provision of motion picture film reels of this type, in which the forces transmitted from the peripheral rims of the flanges through the spokes are applied to the central portions more evenly than heretofore, thereby to avoid unduly high concentrations of stress at particular points on the hub and central portions of the reel.

Finally, it is an object of the present invention to provide motion picture film reels of this type, which will be relatively simple and inexpensive to manufacture, easy and dependable to operate and rugged and durable in use.

Other objects and advantages of the present invention will become apparent from a consideration of the following description, taken in connection with the accompanying drawings, in which:

FIGURE 1 is a view of a motion picture film reel according to the present invention;

FIGURE 2 is an edgewise view of the reel of FIGURE 1; and

FIGURE 3 is an enlarged fragmentary view of a portion of FIGURE 1, showing the distinctive relationships of the structure of the present invention.

Stated very broadly, the present invention comprises the discovery that the distribution of stresses about the central portion of the reel is more uniform if the spokes are disposed non-radially with respect to the axis of the reel, and that improved flexibility without permanent deformation is imparted to the flanges if the thinnest portion of the spokes is disposed more closely adjacent the hub than the rim.

Referring now to the drawings in greater detail, there is shown a motion picture film reel which in its overall configuration may be conventional. Thus, it comprises a pair of flat sheet metal flanges 1 of uniform thickness throughout, disposed in parallel spaced overlying relationship and carrying between them a hub 3 of cylindrical configuration. Each flange 1 comprises a circular outer peripheral rim 5 and a central portion 7, rim 5 and portion 7 being interconnected by a plurality of integral spokes 9 extending therebetween, each pair of adjacent spokes 9 being spaced apart by an opening 11, all the openings 11 being of the same configuration. Central portion 7 is pierced by the usual holes 13 and has the usual non-circular driving hole 15 within which the axis 17 of the reel is located. Hub 3 is comprised of a pair of semi-cylindrical strips 19 disposed in the form of a circle and secured to flanges 1 at spaced points along their opposite edges by means of a plurality of spot welds 21. Of course, the assembly of flanges 1 and hub 3 could be secured together by any convenient method other than welding, such as staking or riveting. The structure of the reel as described thus far is conventional and as such forms no part of the present invention.

The novelty of the present invention is as follows:

The spokes 9 are not disposed along radii of the reel,

2

but rather are inclined thereto at acute angles. Thus, the adjacent ends of openings 11 overlap each other radially outwardly of the reel. Considering the opening 11 which appears in part at the left of FIGURE 3, it will be seen that the line 23, which is a radius of the reel, marks the extreme extent of that opening counter-clockwise, the reel as seen in FIGURE 3. Proceeding clockwise, the other extreme of the opening is marked by the radial line 25. Opening 11 touches line 23 at point 27, while the same opening 11 touches the line 25 at point 29. Point 27 is considerably nearer axis 17 than is point 29, point 29 in the illustrated embodiment being a little more than twice the distance of point 27 from axis 17.

Considering the distance of point 27 from axis 17 to be the distance of the inner end of the openings 11 from the axis, an arc 31 is struck clockwise from point 27 and arc 33 is struck clockwise from point 29. When a line 35 is drawn radially from axis 17 to the inner end of the opening 11 which is at the right of FIGURE 3, this line corresponding to line 23 of the adjacent opening 11, it will be seen that arc 31 intersects this line at point 37 which is also the extreme counter-clockwise point of the right-hand opening 11 of FIGURE 3 and corresponds to point 27. Considering point 37 to mark not only the end of the corresponding opening 11 but also the base of the corresponding spoke 9, it will be seen that the point on arc 31 at the other side of the spoke, designated point 39, marks the other side of the base of the spoke. Correspondingly, the other end of arc 33 from point 29 is marked by point 41, so that the spoke proper extends from arc 33 between points 29 and 41 to arc 31 between points 37 and 39.

With the bounds of the spoke thus established, it will be seen that the spoke has two side edges 43 and 45. Edge 43 is the radially outer edge of the spoke and edge 45 is the radially inner edge of the spoke relative to axis 17. It will also be noted that line 35 intersects edge 43 at point 47, while line 25 intersects edge 45 at point 49, so that edge 43 between points 29 and 47 precisely radially overlies edge 45 between points 37 and 49. Stated another way, edge 43 between points 29 and 47 inwardly bounds that portion of the end of the left opening 11 of FIGURE 3 which precisely radially overlies that portion of the right-hand opening 11 of FIGURE 3 which is outwardly bounded by edge 45 between points 37 and 49.

The configuration of spoke 9 as a whole can thus be observed by consideration of its midline 51, which is a further hypothetical line extending between arcs 31 and 33 and designating the locus of the midpoints of all the arcs lying between and concentric to arcs 31 and 33. Thus, considering for example the boundary arcs 31 and 33, it will be seen that the midpoint of arc 31 is point 53, that is, the point which is equal angular distances between points 37 and 39 relative to axis 17, while point 55 at the other end of midline 51 is the point angularly equidistant between points 29 and 41, so that a radius 57 of the reel passing through point 53 will bisect the angle 37—17—39, while a radius 59 of the reel passing through point 55 will bisect the angle 29—17—41. Midline 51 is arcuate but is not necessarily unicentric. Its center or centers of curvature are all displaced from axis 17 but lie on the same side of line 51 as does axis 17.

The other major feature of the present invention concerns the taper of the spokes such that their thinnest portion, that is, their portion of least cross-sectional area, is substantially nearer base portion 7 than rim 5. As the sheet material of spokes 9, and indeed of flanges 1 as a whole, is of uniform thickness throughout, the reduced cross-sectional feature of the spokes of the present invention is achieved in the illustrated embodiment by progressively decreasing the width of spokes 9 from rim 5 most but not all of the way to central portion 7. Of

course, it will be understood that the same result can be achieved by varying the thickness rather than the width of the spoke.

In FIGURE 3, the cross-section of spoke 9 of least area is designated by a line 61. The significance of line 61 is that if spoke 9 were cut through on that line, the exposed cross-section would then be the least cross-section that could be found along spoke 9. The midpoint of line 61 by chance happens to lie on midline 51, as will happen when edges 43 and 45 adjacent line 61 do not differ markedly from each other in contour; but this is not essential to the invention. The radius from axis 17 which includes point 63 is shown by a line 65. In the illustrated embodiment, line 65 precisely overlies line 35; but this is not essential to the invention and is merely fortuitous. The ends of line 61 at edges 43 and 45 are designated by points 67 and 69, respectively. It will be noted that points 67 and 69 are closer to points 39 and 37, respectively, than they are to points 29 and 41, respectively, just as midpoint 63 is substantially closer to midpoint 53 than to midpoint 55. It will also be noted that points 37 and 69 are substantially closer to each other than are points 39 and 67, but that points 29 and 67 are substantially closer to each other than are points 41 and 69.

Notice also that the boundary of the left-hand opening 11 of FIGURE 3 between points 39 and 27, that is, along edge 43 beyond point 39, is a smooth continuation of the curve from 29 to 39. It should also be noted that each opening 11 is bounded in effect by two large curves, the inner of which extends between points 27 and 29 and the outer of which extends from point 37 along edge 45 beyond point 41, and that both of these curves bow outwardly between the points and lines heretofore discussed, relative to the central portion of the reel.

Spokes 9 are evenly spaced apart about flanges 1, so that the angular displacement of the spokes from each other is equal to 360° divided by the number of spokes. For four-spoke flanges such as are shown, this angle will be 90° ; and hence, angle A of FIGURE 3, between lines 23 and 35, is a right angle. The angle by which adjacent ends of openings 11 radially overlap each other is also significant and is represented by the angle B between lines 25 and 35. According to the present invention, this angle is an acute angle and in the illustrated embodiment is about 25° . Another angle of significance is the mean angle subtended by the spokes, that is, the angle subtended by midline 51 between boundary arcs 31 and 33. In FIGURE 3, this angle is designated as angle C, between lines 57 and 59, and in the illustrated embodiment is about 45° . Finally, another significant angle is the angle, or complement of the angle, by which line 61 deviates from orientation perpendicular to radial line 65. For a spoke disposed precisely radially, as in the prior art, line 61 would be precisely perpendicular to line 65, and the angle D between these lines would be 90° . According to the present invention, however, angle D is always an acute angle, that is, an angle less than 90° , and in the illustrated embodiment is about 45° . This means that at line 61, which is the line of greatest flexure, the flexure of the spoke is not in a radial plane but in a plane displaced from any radius of the reel. It should also be noted that at all points along midline 51, the corresponding radius of the reel forms the same acute angle with the tangent to midline 51 at that point. Thus, midline 51 progressively recedes from axis 17.

The significance of all these novel structural features and relationships is as follows:

In general, the direction of the spokes away from the axis of the reel assures that stresses applied in directions non-parallel to the plane of the flanges will be distributed more evenly about the hub and base portion of the reel than if the spokes were radially disposed, that is, than if midline 51 coincided with a radius of the reel. As a refinement of this feature, the fact that spokes 9

extend arcuately outward rather than straight outward on an incline, that is, the fact that midline 51 is arcuate in the manner shown rather than straight, throws even more of these nonparallel stresses to the side of the spokes away from axis 17, with the result that stresses that might tend to be applied, say, at point 53 are instead applied more toward point 39 and thus are carried on about the periphery of central portion 7 toward point 27. In other words, the inclination of spoke 9, and more particularly the arcuate inclination of spoke 9, tends to spread out the forces applied to base portion 7 toward the next spoke 9, or counter-clockwise according to the configuration of the spokes in FIGURE 3. Concomitant features by which this relationship may be expressed in terms of particular structure are that the end portions of openings 11 overlap each other with the end points 29 and 37 spaced distinctively different radial distances from axis 17, that edges 43 overlap each other at least between points 29 and 47 and 37 and 49, that the marginal edges of openings 11 are outwardly bowed, that the angle C is acute and is greater than the angle B, and that midline 51 subtends the radii of the reel over a substantial angle and is disposed at an acute angle to all the radii that intersect it. Thus, all these features coact to assure that the stresses are applied by the spokes more evenly about the base portion and the hub of the reel, with the result that the flanges have less tendency to tear loose from the hub than in the prior art. This reduced tendency of the hub and flanges to separate from each other or for the reel to come apart adjacent its hub is useful not only in the illustrated reel but in a variety of other forms of reels, for its has been a problem common to a great variety of reels that stresses applied out of the planes of the flanges tend to damage the reels adjacent the hubs.

The provision of the least cross-sectional area of the spokes more closely adjacent the hub from the rim assures that a given displacement of the rim from its normal plane can be accommodated with the least bending of the flanges in such a manner as would permanently deform them. The most bending occurs where it does the most good in terms of rim deflection, namely, at locations progressively farther from the rim toward the hub. While each of these two features (spokes inclined, and spokes inwardly thinned) comprises a patentable feature of the present invention in and of itself, the coaction of these two features comprises a third patentable feature of the invention. Specifically, the orientation of the spokes permits the increased flexure feature to be useful without imposing undue stresses on the base portion of the flanges. If the flanges were radially disposed and line 61 were perpendicular both to the midline of the spoke and to the radius from axis 17 that bisected line 61, then increased flexure about line 61 close to the hub according to the present invention would impose greater stress on the hub and base portion of the reel closely adjacent the point corresponding to point 53 than if line 61 were farther out as in the prior art. Thus, the increase in flexibility would be bought at the price of tending to tear the flanges loose from the hub adjacent point 53. But according to the present invention, means are provided for dispersing what would otherwise be this more concentrated stress, these latter means comprising the spokes oriented as described above. Hence, it is a significant feature of the invention that the line 61 is in effect turned away from confronting relationship with the axis of the reel, so that a line perpendicular to line 61 point 63 at no point passes close to axis 17; and this feature is significant not only in its own right but also in combination with the feature of forming the spokes thinnest adjacent the hub.

From a consideration of the foregoing disclosure, it will be obvious that all of the initially recited objects of the present invention have been achieved.

It is to be understood that the appended claim is to

be accorded a range of equivalents commensurate in scope with the advance over the prior art.

What is claimed is:

A motion picture film reel, comprising a pair of flanges of flat resilient sheet material with a central hub between them, each flange having an outer peripheral rim supported by a plurality of spokes that extend between and resiliently interconnect the hub and the flange, each spoke being of uniform thickness and tapering from the rim toward the hub to a least width substantially closer to the hub than to the rim, said least width being inclined at an acute angle of about 45° to that radius of the reel which bisects said least width, each spoke having a midline that intersects the radii of the reel over a substantial angle about the reel and the spokes spiraling outward from the hub to the rim so that all paths from the

rim to the hub are elongated thereby to minimize the curvature of the spokes when a portion of the rim is resiliently displaced from the plane of the remainder of its flange, said angularly inclined least width serving during such displacement to deflect the bending stresses imposed on the hub away from the axis of the hub and toward the periphery of the hub.
